IGNITION SWITCH LOCK FOR AUTOMOBILES

Filed Sept. 29, 1927

UNITED STATES PATENT OFFICE

FREDERICK W. ANDREW, OF ANDALUSIA, PENNSYLVANIA, ASSIGNOR, BY MESNE ASSIGNMENTS, TO THE ELECTROLOCK MANUFACTURING COMPANY, OF VICKSBURG, MISSISSIPPI, A CORPORATION OF MISSISSIPPI

IGNITION-SWITCH LOCK FOR AUTOMOBILES

Application filed September 29, 1927. Serial No. 222,712.

My invention relates to ignition switch locks for automobiles and the like and it has for its general object to provide a switch lock of novel construction including means actuated upon the locking of the switch to open 5 the same and break the ignition circuit.

It also is an object of the invention to provide a switch including means of novel construction whereby upon the actuation of the locking means thereof into locking position 10 the switch is opened to break the ignition circuit and at the same time the switch casing is locked to stationary portions of the automobile structure upon which the switch is mounted.

Another object of the invention is to provide an ignition switch having a lock in which the locking bolt is provided with means which operates automatically upon its 20 movement into locked position to break the ignition circuit and simultaneously to ground a portion of the said circuit.

To these and other ends my invention comprehends the construction and arrangement 25 of parts as hereinafter described in detail, particularly pointed out in the claims and illustrated in the drawing in which I have shown one form of mechanical embodiment of the said invention. However, it will be 30 understood that the invention may be embodied in other forms of construction than that shown and that changes in the details of construction may be made within the scope of the claims without departing from the said 35 invention or the principle thereof.

In the drawing:

Fig. 1 is a view in longitudinal vertical section of an ignition switch lock embodying the invention;

Fig. 2 is a similar view with certain of the 40 parts shown in different position from what they are shown in Fig. 1;

Fig. 3 is a transverse sectional view taken on the line 3—3 of Fig. 1;

Fig. 4 is a transverse sectional view taken 45 on the line 4—4 of Fig. 2; and

Fig. 5 is a transverse sectional view taken on the line 5—5 of Fig. 1.

In the drawing I have shown portions of 50 conducting wires 1 and 2, the former of which

extends to and is connected with the timer-distributor, not shown. The latter wire 2 is extended to and connected with one end of the primary coil of a transformer, the other end of the latter being connected to a battery or other source of electric energy, neither the transformer nor the battery being shown. The circuits are completed through "ground" in known manner and in consequence a diagram thereof is not shown. The relative arrangement or succession of the parts in the conducting line 2 may be varied if desired from what is above suggested. The conducting wire 1 leading to the timer-distributor is protected by coiled wires 3 and 4 to prevent access thereto. The end portion of the wire 4 which is illustrated in the drawing is mounted permanently within a thimble 4^a consisting of an extension of the inner end portion of the switch lock casing 5. The conducting wire 1 is connected within the lock casing 5 to a metal terminal 6 which is detachably mounted within a metal sleeve 7 which in turn is mounted within an opening 8 provided within a block 10 of insulating material. The outer end of the sheathing 14 of insulating material around the conducting wire 1 extends through an opening in a disk 14^a of insulating material mounted within the casing 5 between the block 10 of insulating material and the adjoining end of said casing.

A spring contact 15 is secured to the terminal 6 and supported thereby. The said contact is provided with a transversely extending portion 17, having an opening there-through as shown through which the terminal 6 passes. The outer end of the said terminal is upset as indicated so as to secure the said contact 15 thereto. The contact 15 is of spring metal and by reason of its spring action normally contacts with the inner end of a contact terminal 20 mounted in the block 10 of insulating material and extending transversely thereof. The outer end portion of the terminal 20 is provided with an axial opening therein which is screw-threaded for the reception of the screw-threaded outwardly projecting binding post 21. The latter extends outwardly through an opening in a bushing 22 of insulating material located 55 60 65 70 75 80 85 90 95 100

within an opening 23 in the side of the casing 5. One end of the conducting wire 2 is connected to the binding post 21 in known manner and as illustrated in Figs. 1 and 2. The 5 casing 1 extends outwardly through a split lining or sleeve 25 mounted within a tubular inwardly projecting support 26 provided with an outwardly extending flange at its forward end as indicated at 27 which is secured to the dash board 28 of the car by means of rivets as indicated at 29 or by any other suitable means, as by spot welding. The split lining or sleeve 25 is permanently secured to and within the tubular support 26 by means of spot welding as indicated at 30 or otherwise. The point of connection 30 is illustrated as being located near one end of the lining or sleeve 25 but such point of connection may be otherwise located and may be 10 duplicated but the opposite end portion thereof, or at least one end portion thereof, should be free or disconnected from the tubular support 26 in order that the said sleeve may be caused to clamp the casing 5. In 15 order to effect clamping action of the lining or sleeve 25 upon the said casing the opposite ends of said sleeve are provided with lateral projections as indicated at 31 which project outwardly through a slot or notch 32 in the tubular support 26 previously referred to. The projections 31 are provided with openings through which a tightening bolt 33 extends the tightening and the loosening thereof being effected by means of a nut 34 20 in obvious and known manner.

A lock cylinder 40 is mounted within the outer end portion of the casing 5 and is reciprocable therein. The said cylinder is provided with a transversely movable locking 25 bolt 41 which is adapted to be actuated into unlocked position by means of a key indicated in dash and dot lines at 42. A spring, not shown, tends to cause outward movement of the said bolt in a direction transversely of the cylinder 40. The bolt 41 is provided with a pin 43 secured thereto at a point intermediate its ends, which pin extends in a direction parallel with the axis of the cylinder 30 and with the axis of the casing 5. The pin 43 extends through a slot 45 provided in the inner end wall 46 of the lock cylinder structure. When the lock is moved inwardly into locking position the locking bolt 41 is moved 30 outwardly through an opening 47 in the casing 5 and into an opening 48 in the lining or sleeve 25. When in such position the lock casing 5 is locked to the lining or sleeve 25 and the tubular support 26. In moving the 35 lock cylinder 40 inwardly to the position as illustrated in Fig. 2 of the drawing a coiled spring 50 which is located between the inner end of the lock cylinder and the block 10 of insulating material is compressed. Upon removal of the bolt 41, by means of the key

42, from the openings 47 and 48 the spring 50 expands to effect outward movement of the lock cylinder 40 and bolt 41 into the position shown in Fig. 1. The pin 43 previously referred to is located in cooperative relation to the outer end of the spring contact 15 to which reference has been made previously. When the lock is moved inwardly into the position shown in Fig. 2 of the drawing the said pin contacts with the outer end of the spring and depresses or moves the same laterally out of contact with the stationary terminal contact 20 to break the ignition circuit. At such time the conducting wire 1 having connection at one end to the timer-distributor as previously stated is grounded through the lock structure which is mounted upon the metal car structure.

Rotation of the lock cylinder within the casing 5 is prevented by means of a screw 51, the inner end of which is in screw-threaded engagement with the said cylinder while the outer end thereof is located within a slot indicated by dotted lines at 52 in Figs. 3 and 4.

It will be seen that by my invention I am enabled to provide a switch lock of simple construction in which, when the lock is moved into locking position, the switch is locked to its support and cannot be removed therefrom except by one having a key adapted to the lock; also that the locking bolt is provided with means whereby upon movement thereof into locking position the ignition circuit is broken and a portion thereof grounded through the metal supporting structure.

Having thus described my invention, what I claim and desire to secure by Letters Patent is:

1. In an ignition switch lock, the combination of a switch casing, a movable contact therein which normally is in closed position, and a lock cylinder mounted within and adapted to reciprocate in the said switch casing, said cylinder having a locking bolt provided with means whereby movement of said bolt into locking position to lock the cylinder to the said casing effects opening movement of the said movable switch contact.

2. In an ignition switch lock, the combination of a switch casing, a support for said casing, a movable contact therein which normally is in closed position, a lock cylinder mounted within the said casing and adapted to reciprocate therein, said cylinder having a locking bolt which is adapted to reciprocate transversely of the axis thereof, said bolt having means which when it is moved outwardly into locking position engages with the said movable contact and effects opening movement thereof, and means whereby when the said

bolt is moved into locking position it operates to lock the said casing to its support.

3. In an ignition switch lock, the combination of a switch casing, a support upon which said casing is adapted to be detachably mounted, movable and stationary contacts mounted within the said casing, the said movable contact being normally in contact with the stationary contact, a lock cylinder mounted within the said casing and adapted to reciprocate therein, said cylinder being provided with a radially movable locking bolt having a pin extending laterally therefrom in parallel relation to the axis of said cylinder, which pin, when the bolt moves into locking position, contacts with the said movable contact to effect opening movement thereof, and means whereby, when the said locking bolt is moved into locking position, the said switch casing is locked to the said support.

10 4. In an ignition switch lock, the combination of a switch casing, a support therefor provided with a sleeve within which said casing is adapted to be mounted, the said casing and sleeve having openings which are in registry with each other, stationary and movable contacts mounted within the said casing, and a lock cylinder mounted within said casing and adapted to reciprocate therein, which cylinder is provided with a locking bolt which is reciprocative radially of the said lock cylinder, said locking bolt having a pin which projects inwardly therefrom substantially in parallel relation to the axis of the said cylinder, which pin, when the said bolt moves into locking position, contacts with the said movable contact to move the same into open position to break the ignition circuit, and the outer end of the said locking bolt entering the openings of the said casing and sleeve whereby the said casing is locked to the said sleeve.

15 5. In an ignition switch lock, the combination of a tubular support permanently secured to a suitable portion of an automobile structure, a lining for said support, which lining is permanently secured thereto, a casing movably mounted within said lining, the said casing and lining having registering openings in their sides, a movable contact mounted within said casing, said contact normally being in closed position, and a lock cylinder mounted to reciprocate in the outer end portion of said casing, said cylinder having a locking bolt which is adapted to reciprocate radially thereof, the outer end of which bolt when in locked position enters the said openings to effect locking of the said casing within said lining and the said locking bolt being provided with a pin which extends inwardly therefrom in parallel relation to the axis of the said lock cylinder, which pin, when the locking bolt is in unlocked position is in laterally spaced relation with

16 gages the same when the said bolt is moved into locking position to effect movement thereof into open position.

6. In an ignition switch lock, the combination of a switch casing, a support therefor, stationary and movable contacts mounted within said casing, the said movable contact normally being in closed position, a lock cylinder mounted within said casing and adapted to be moved therein into and out of locking position, and means acting automatically upon the movement of said lock cylinder into locking position to move the said movable contact into open position and effect grounding of the said movable contact.

7. In an ignition switch lock, the combination of a switch casing, a support upon which said casing is detachably mounted, stationary and movable contacts mounted within said casing, the said movable contact normally being in closed position, a lock cylinder mounted within the said casing and movable therein into and out of locking position, and means operative upon the movement of said lock cylinder into locking position to effect movement of the said movable contact out of engagement with the said stationary contact and to ground the said movable contact and to effect locking of the said casing to its support.

8. In an ignition switch lock the combination of a switch casing, a movable contact therein which normally is in closed position, and a lock cylinder mounted within and adapted to reciprocate in the said switch casing, said cylinder having a locking bolt and a pin mounted on the said bolt, the said pin being adapted to engage the movable contact to open the same when the said bolt moves into locking position to lock the cylinder to the said casing.

9. In an ignition switch lock the combination of a switch casing, a support for the said casing, said casing and support having openings in their side walls which are in registry with each other, a movable contact mounted in the said casing which normally is in closed position, a lock cylinder mounted within and adapted to reciprocate in the said switch casing, said cylinder having a locking bolt which is adapted to enter said openings to lock the said casing support and cylinder together, and a pin mounted on the said bolt adapted to engage the said contact when the said bolt is moved into locking position to open the same.

In testimony that I claim the foregoing as my invention I have hereunto signed my name this 23rd day of September, A. D. 1927.

FREDERICK W. ANDREW.
